Primary Examiner — Gino Colan(74) *Attorney, Agent, or Firm* — Ryan Kromholz & Manion, S.C.(57) **CLAIM**

The ornamental design for a climbing stick, as shown and described.

DESCRIPTION

FIG. 1 is a perspective view of a climbing stick;
 FIG. 2 is a first side view of the climbing stick;
 FIG. 3 is a second side view of the climbing stick;
 FIG. 4 is a third side view of the climbing stick; and,
 FIG. 5 is a fourth side view of the climbing stick.
 All broken lines illustrate portions of the climbing stick that
 form no part of the claimed design.

1 Claim, 2 Drawing Sheets(56)
